UNITED STATES PATENT OFFICE.

FRANK J. SCHROEDER, OF ALTOONA, PENNSYLVANIA.

RAIL LOCK.

Application filed October 14, 1927. Serial No. 226,152.

This invention relates to anti-creeping devices designed for use in connection with railway rails.

- An important object of the invention is to provide a device of this character which will be free of bolts and nuts, novel means being provided for clamping the device on a railway rail at a point adjacent to a tie so that the device will abut the tie.
- 10 A still further object of the invention is to provide a device of this character which may be secured by hitting the device with a sledge hammer or the like to cause the device to be securely held in position by the 15 resiliency of the metal of which the device is formed.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 25 within the scope of what is claimed, without departing from the spirit of the invention.

Referring to the drawing:

Figure 1 is a vertical sectional view through a rail equipped with an anti-creep 30 constructed in accordance with the invention.

Figure 2 is a fragmental elevational view of a rail showing the anticreeper as secured thereto.

35 Figure 3 is a sectional view taken on line 3-3 of Figure 2.

Referring to the drawing in detail, the reference character R designates a railway rail, to which the anti-creep forming the 40 subject matter of this invention is secured.

The anti-creep includes a body portion indicated generally by the numeral 5 which has inwardly extended end portions 6 designed to rest under the rail to which the 45 device is secured, the body portion being also provided with an upstanding inwardly disposed flange 7 adapted to overlie a portion of the base of the rail in a manner as shown by Figure 1.

50 Formed in the body portion 5 is an elongated opening 10 and a lateral opening 11 that communicates with the opening 10, there being provided a projection 12 adjacent to the openings 10 and 11, for purposes to be hereinafter more fully described.

Depressions 13 and 14 are formed in the

body portion above the openings 10 and 11, the depression 13 being deeper than the depression 14 so that when the upstanding end 15 of the securing member 16 is being positioned, the upstanding end portion may be received within the depression 13 and held until the same is finally moved to a locking position within the depression 14.

Formed integral with one end of the securing member 16 is a hook 17 that hooks over one edge of the base of the rail to which the device is secured, it being understood that one of the end portions 6 is moved into close engagement with a railway tie on 70 which the rail is positioned. When the device is positioned on a rail, and the securing member 16 is in a position as shown by Figure 2 of the drawing, the upstanding portion 15 thereof is struck with a sledge hammer or other suitable instrument, and caused to move to engage within the depression 14.

It will be seen that should the securing member 16 for any reason become loose, and drop down, it will be held to the rail by the 80 action of the projection 12 and prevented from moving laterally.

I claim:

1. An anti-creep for railway rails including a body portion having inwardly disposed end portions fitted under the rail and having an upstanding flange overlying the upper edge of the rail, said body portion having an opening, a securing member having a hook at one end hooked over the base 90 of the rail and having an upstanding end portion extended through the opening of the body portion, and depressions in the body portion to receive the upstanding end of the securing member.

2. An anti-creep for railway rails including a body portion having parallel ends extended inwardly to fit under a rail, said body portion having openings, said body portion having depressions above the openings, the depressions being of various depths, a securing member including a rod having a hook formed at one end to be hooked over the rail, and having an upstanding end extending through one of the openings and resting in the depression thereabove, and said upstanding end adapted to be moved laterally to contact with the adjacent depression to lock the securing member to the rail.

3. An anti-creep for railway rails including a body portion fitted over a flange

of the base of a rail, said body portion having openings formed therein, a projection formed between the openings, a securing member fitted under the rail, and having a hook portion hooked over the base of the rail, the opposite end of the securing member extending through one of the openings

and adapted to be forced laterally into the adjacent opening, and said projection adapted to prevent lateral movement of the securing member. 10

In testimony that I claim the foregoing as my own, I have hereto affixed my signature.

FRANK J. SCHROEDER.
